Fig. 4

FIG. 1 is a front elevation of the string light socket, embodying my new design, the back being substantially the same;

FIG. 2 is a side elevation of the right side of the string light socket illustrated in FIG. 1, the left side being substantially the same; and

FIGS. 3 and 4 are top and bottom views, respectively, of the string light socket illustrated in FIG. 1.

The dominant features of my design reside in the solid line portion, the broken line showing of wires being for illustrative purposes only.

I claim:

The ornamental design for a string light socket, as shown and described.
